UNITED STATES PATENT OFFICE.

CHARLES STOREY WHEELWRIGHT, OF BRISTOL, RHODE ISLAND,
ASSIGNOR TO AMERICAN EXTRACTOR COMPANY, A CORPOR-
ATION OF MAINE.

CONVEYING AND PRESSING APPARATUS.

SPECIFICATION forming part of Letters Patent No. 783,602, dated February 28, 1905.

Original application filed May 24, 1904, Serial No. 209,553. Divided and this application filed November 5, 1904. Serial No. 231,593.

To all whom it may concern:

Be it known that I, CHARLES STOREY WHEELWRIGHT, of Bristol, in the State of Rhode Island, have invented a new and useful 5 Improvement in Conveying and Pressing Apparatus, of which the following is a specification.

The object of the invention is to convey tankage or refuse from a vessel in which garbage or offal has been subjected to the hot-water process for the removal of melted grease therefrom to a drying apparatus or platform, where it may be dried for fuel; but it is obvious that the conveyer and presser is applicable for other uses. The invention, however, will be described as adapted for use with a rendering plant.

The invention consists of a long water-tight cylinder provided with a carrying-screw fitting its inner periphery and extending to near the end of said cylinder, perforations in said cylinder and suction-boxes working in connection with said perforations, an extension to said cylinder, a valve in said extension at some 25 distance from the end of said screw filling the inner periphery of said extension, and an outlet in said extension, whereby material saturated with water and accompanied by water dumped into said cylinder loses its free water 30 through said perforations and suction-boxes and is borne along by said screw until it packs under the influence of said screw in the space between the end of said screw and said valve, when the valve being opened the tankage as a 35 continually-forming stopper passes under the force of the screw out of the opening controlled by the said valve.

A device for imparting frictional resistance to the wet material passing through the conveyer and presser that it may not merely turn in the screw and fail to be carried along forms an important feature of the invention.

The invention consists, further, in details of construction.

In the drawings hereto annexed and forming a part of this specification, Figure 1 is a longitudinal view of the conveyer and presser,

together with so much of a digester, water-tank, pump, and connecting-pipes as is necessary for an understanding of the invention and 50 its said use in combination with a rendering plant. Fig. 2 is a longitudinal cross-section of the conveyer and presser, showing within the cylinder the conveying-screw, the suction-boxes, vibrating plate or fin, and valve, with 55 mechanism for operating the valve. Fig. 3 is a cross-section of said cylinder on a still larger scale, showing, however, only two fins. Figs. 4 and 5 are details.

A represents so much of a digester as it is 60 necessary to show in a description of the apparatus by which the above-mentioned process as relating to garbage is conducted. A pipe A', by which live steam is fed to the digester, is also shown. The digester has a valved outlet A², near the bottom thereof, of a diameter 65 as large or even larger than that of the cylinder next described and with which the said outlet communicates near the closed end of the cylinder, as shown.

B is a long cylinder, through the center of which, closely fitting its inner periphery, is a sixteen-inch screw C. This is the dimension 75 of the screw actually used by me and from it the dimensions of the remaining parts of the apparatus may be readily ascertained, although I do not limit myself to the dimension shown.

The cylinder B, provided with lugs d d, is supported upon standards D. An extension of the cylinder beyond the screw is marked B', 80 which may be of different lengths, but is of the same diameter as cylinder B, and beyond this extension B' is a second extension B² of substantially the same diameter, which is provided with an outlet at B³. The screw C is secured 85 to said shaft E by splines and a feather c and revolves with said shaft, which extends outside of the cylinder B through the extensions B' and B². The said shaft E has bearings or supports at e in the end piece B⁴ of the cylinder B, a being a collar surrounding the shaft 90 and set into the screw, as shown, a' being a ring of soft metal between said screw and the end piece B⁴, and a² being disks of soft metal

between the shaft E and said end piece B⁴, as shown, and at e' a long box supported upon a standard D' outside of the cylinder B and its two extensions B' and B². The shaft E carries 5 a large beveled gear G, into which takes a small beveled gear (not shown) carried upon the counter-shaft of the driving apparatus. The extreme end of the cylinder B² is provided with a head d², in which fits a packing-box I, 10 provided with a gland I', the office of which is to furnish a suitable packing or bearing for a hollow shaft J, moved on and along shaft E by a hand-wheel J', a nut J², rigidly connected with said hand-wheel, and a screw-thread J³ 15 upon said shaft E, the said movable shaft J carrying with it a valve-disk K, provided with teeth K' K', as shown. The valve-disk K has a seat at L in the rim of the extension of the cylinder B', and the peculiar shape of the face 20 of the valve directs material or tankage sent forward by the screw C and packed or packing in extensions B' B² downward out of the outlet at B³ at any position of the valve-disk as removed any distance from its seat by manipulating hand-wheel J'. The valve, whatever 25 its position longitudinally in extension B², constantly revolves with the shaft E, and thereby with the help of the teeth K' K' breaks up the material forced forward by the screw C and directed toward the outlet B³.

M M are two suction-boxes, similar to those used in paper machinery for a like purpose, operated by two suction pipes or outlets N N in connection with perforated plates O O, set 30 into and forming a part of the cylinder B. These suction-boxes are of peculiar shape and are hinged to the cylinder B, being so far removable therefrom as to permit of the removal and insertion of the perforated plates O, as 35 will presently be more particularly described. It is sufficient for the present to point out that the two suction-pipes N N, the principal office of which is to draw water from the cylinder through the plates O O, connect with a 40 force-pump N', which feeds a pipe N², emptying into the top of the digester A or the top of a water-tank N³, extending lengthwise alongside of the digester, accordingly as valves shown in connection with said pipes are manipulated. This tank N³ is provided with a 45 pipe N⁴, opening from the bottom of the tank and communicating with the outlet A² from the digester below the valve therein. It is provided with a check-valve N⁵ and an ordinary valve N⁶. The pipe N² has valves N⁷ N⁸ 50 N⁹ and is provided with a branch pipe N¹⁰, communicating with the top of the digester from between valves N⁸ and N⁹ and in turn provided with a valve N¹¹. The office of the 55 various valves shown in the drawings is obvious. One of the suction-boxes is shown at Fig. 3 in cross-section, together with the perforated plate and adjacent parts of the cylinder and devices by which the suction-box 60 is hinged to the cylinder, so that the suc-

tion-box falling back on the hinge the perforated plate may be removed from the cylinder. M in this figure, as stated above, is one of the suction-boxes, and Q is one of the perforated plates set into the cylinder B. M' 70 is one of several bars to support or hold up the perforated plate O, the said bars being cast with the box M. The box M is hinged to the cylinder B (see Fig. 5) by means of two lugs b b, cast on the cylinder, a fork m m, 75 cast upon the box M so as to fit inside of said lugs b b, and a bolt m' passing through the said fork and lugs and also through an eccentric n², which fits between the lugs b b and is swung by a lever n³. When the box is 80 set free at the other end, as will now be described, and the eccentric n² is loosened by swinging back the lever n³, the box swings back on the bolt m', carrying with it the supporting-bars M'. The office of the eccentric 85 n² is to tighten the box M in its working position. The locking apparatus at the other end of the suction-box (see Fig. 4) consists of two lugs b² b², cast upon the cylinder B, a 90 swivel-pin n, pivoted by a bolt n' to the said lugs b² b² and embraced by forked arms n⁵ n⁵, which are cast upon the box M and are held in the position embracing said swivel-pin by a nut n⁴ working on a screw-thread on the end of said swivel-pin and operated by a handle n⁶. 95

The office of the screw E, as has perhaps already appeared, is to carry forward in the cylinder or through the cylinder and extensions thereof the more solid parts of the contents of the cylinder; but this the screw sometimes fails to do, owing to the moist and slippery nature of such material or substance. The greasy mass is apt to turn with the screw without being moved forward. This difficulty is in part remedied by the frictional resistance imparted to the mass by the above-mentioned suction-boxes M M, a pull or suction being exerted upon the mass in a direction substantially at right angles to force exerted by the screw. Another device for imparting frictional resistance to the slippery material held in the thread of the screw consists of certain movable pieces of metal, which I term "vibrating" fins P P, whose movements into and out of the mass are controlled 100 by the screw acting upon their edges automatically. These fins are very numerous and are placed in pairs about the screw, (see Fig. 1,) so that a separate fin works in each interval between two screw-threads. They are 105 made of soft metal and have their peripheries cam-shaped, as shown, so as to follow with an up-and-down or in-and-out vibrating motion the convolutions of the screw, the points and heels of the fins dipping into the wet and slippery mass forced forward by the screw between the threads and rising therefrom successively one fin from another, so that the material between the screw-threads is struck 110 by the fins in various positions. They are so 115

secured to the cylinder that they and the mechanisms by which they are attached may be readily removed. One form of these fins, with accompanying parts, is shown in detail at Fig. 3, where P is the fin pivoted upon axis P', as shown. B is the cylinder. P² P² are long guides let into the cylinder, as shown, for two fins and held in place by screw-bolts P³ P³, secured by nuts P⁴ P⁴. A long cap P⁵ covers the said two guides P² P² and the space in which the fin works, as shown, being held in place by a lever P⁶, forked at q where it is pivoted on a pivot-pin q', held in place by nuts q' q'. The other end of lever P⁶ is forked at q³ to embrace a swivel-pin P⁷, pivoted on pivot q⁴ and held in place in the fork q³ of lever P⁶ by a nut P⁸ working on a screw-thread on the end of swivel-pin P⁷ and provided with a hand-lever P⁹. The pivot-pin q' has bearings in shoulders P¹⁰ and the pivot q⁴ has bearings in shoulders P¹¹, the said shoulders P¹⁰ and P¹¹ being ears or lugs cast on the guides P² P².

The cylinder B has been described as a cylinder with an extension or extensions. It is obvious, however, that the cylinder with its extensions may be considered as a single piece of apparatus or as a cylinder containing a screw which does not reach to its end, but leaves a projection containing a chamber beyond the end of the screw, into which material forced forward by the screw may accumulate and finally be removed by other devices.

As before stated, the conveying and pressing apparatus above described is particularly adapted for use in connection with the rendering plant.

The operation is as follows: The digester A is supposed to be full of tankage and hot water and the tank N³ is supposed to be full of water more or less heated and all steam-pressure has been blown off from the entire apparatus. The handle J' is turned and the valve K brought to its seat at L, thereby closing the cylinder and rendering the system consisting of the cylinder and all apparatus heretofore described as connected therewith water-tight. The valve N⁶ is next opened and the cylinder fills with water from the tank N³. The screw C is now started and the valve in pipe A² is opened, when the tankage or whatever material other than water may be in the digester descends through the pipe A² and first displacing so far as may be the water in the cylinder through the perforated plates and suction-boxes gradually fills the screw C and gradually packs in the space B' between the end of the screw and said valve K, forming a stopper to the cylinder. The valve K is finally opened and the pressed material as a continuously-forming stopper passes forward under the force of the screw against the retired valve into the extension B³, whence broken up by the blades K' K' of the valve it passes out of the conveyer and presser

through the outlet at B³ to a drying mechanism or drying-platform. (Not shown.) When the valve in the large pipe A² is opened, the valves N², N⁸, and N⁹ are opened and the pump N' is started, and the valve N¹¹ is opened as often as it may be necessary.

This application is a division of my application, Serial No. 209,553, filed May 24, 1904, in which the herein-described conveying and pressing apparatus is shown and described as used with a rendering plant, the object of this application being a separate patent for such conveying and pressing apparatus independent of its use with a rendering plant.

I claim—

1. In a conveying and pressing apparatus adapted to convey and press material saturated with and accompanied by water, the combination of a water-tight cylinder provided with a long carrying-screw fitting the internal periphery of said cylinder and adapted to revolve therein, perforated plates let into said cylinder, suction-boxes adapted to work in connection with said perforated plates, a projection or extension of said cylinder beyond said carrying-screw, an outlet to said cylinder in said extension, and a valve having its seat in said extension between the end of said carrying-screw and said outlet at some distance from said screw, adapted to open or close said outlet substantially as described.

2. In a carrying and pressing apparatus adapted to convey and press material saturated with and accompanied by water, the combination with a water-tight cylinder provided with a carrying-screw filling the internal periphery of said cylinder and adapted to revolve therein, perforated plates let into said cylinder, suction-boxes adapted to work in connection with said perforated plates, a projection or extension of said cylinder beyond said carrying-screw, an outlet in said extension and a valve having its seat in said extension between the end of said carrying-screw and said outlet, of vibrating plates or fins adapted to vibrate into and out of the interstices between the threads of said carrying-screw, substantially as described.

3. The combination with a water-tight cylinder provided with a carrying-screw fitting the inner periphery thereof and adapted to revolve therein, and perforated plates let into said cylinder, of vibrating plates or fins adapted to vibrate to and from the interstices between the threads of said carrying-screw, substantially as described.

4. In a carrying and pressing apparatus adapted to operate upon substances saturated with and accompanied by water, the combination of a water-tight cylinder, carrying a screw fitting its internal periphery and adapted to revolve therein, perforated plates let into said cylinder, suction-boxes adapted to draw water from said cylinder through said perforated plates, and vibrating plates or fins

adapted to vibrate to and from the interstices between the threads of said screw, substantially as described.

5. In a conveying and pressing apparatus for handling tankage consisting essentially of a long cylinder and a screw fitting the internal periphery of said cylinder and adapted to revolve therein, the combination with said cyl-

inder of removable perforated plates and removable suction-boxes adapted to draw water from said cylinder through said perforated plates, substantially as described.

CHARLES STOREY WHEELWRIGHT.
